UNITED STATES PATENT OFFICE

CARROLL BURTON, OF JOHNSTOWN, PENNSYLVANIA

GUARD RAIL

Application filed April 16, 1932. Serial No. 605,685.

This invention relates to railway track structures and particularly to an improved type of guard rail adapted for use in accordance with the conventional practice in the art in the vicinity of switches, frog points and curved tracks for the purpose of coacting with wheel flanges to avoid derailment.

Various types of guard rails have been heretofore used for this general purpose. They are frequently made of sections of ordinary rolled rail or castings of steel or alloy steel of various configurations to meet requirements.

My invention aims to provide a guard rail which can be forged or pressed from a substantially flat plate of uniform thickness. This effects certain economies in the process of manufacture yet provides an article which is equal or in some cases superior to similar articles heretofore available. The improved guard rail is formed preferably of wrought or rolled plate stock and is inherently strong and well able to resist the stresses to which such articles are subjected and at the same time it is relatively lighter in weight than guards heretofore available for the same class of service. This reduction of weight obviously effects a saving in manufacturing costs.

The invention further consists in the novel design and arrangement of the component parts of the structure, all as more fully hereinafter pointed out in the specification and claims.

In the accompanying drawing, which illustrates one embodiment of the invention—

Fig. 1 is a top plan view, showing my improved guard mounted in juxtaposition to a traffic rail, the guard rail and traffic rail being carried by the usual cross ties;

Fig. 2 is a detail side elevation of the guard rail alone;

Fig. 3 is an end elevation viewed from the left end of Fig. 1;

Fig. 4 is a transverse vertical section on line 4—4 of Fig. 1.

Referring in detail to the drawing, numerals 10 represent any usual or suitable railway track supporting structure such as wooden cross ties commonly employed. Mounted on these ties by a plurality of spikes 12 is a

guard rail, indicated generally at 14, embodying the present invention. My improved guard rail includes a rail seat portion 16, which provides a bearing for the base flanges of the traffic rail 17. Extending upwardly from the rail seat portion, the guard rail is formed with an upstanding wall 18 herein referred to as the outboard wall. This outboard wall is joined by a top portion 20 with an inboard wall portion 22, which is slightly inclined to the vertical, as indicated in Fig. 4. The lower part of the inboard wall 22 merges into a laterally extending bearing flange 24. This bearing flange has wings 26 at spaced intervals, which wings are apertured, as indicated at 28, for the reception of spikes or other anchorage devices.

To reinforce the guard rail, I provide a plurality of hollow ribs 30, which are formed by bulging or outwardly expanding the inboard wall 22 at suitable intervals. In the embodiment of the invention illustrated, these reinforcing ribs 30 are in line with the wings 26. The reinforcing ribs, as shown, are relatively wide at the bottom and converge upwardly, thus merging gradually into the upper part of the inboard wall.

The central portion of both the outboard and inboard walls 18 and 22 are substantially or approximately parallel with the traffic rail 17. This parallel portion extends approximately from the points 32—34. In this central parallel portion of the guard rail, the cross section thereof is of substantially channel-shape in cross section, the inboard and outboard walls being spaced apart, as clearly shown in Fig. 4. As these two walls approach the extremities of the guard rail, they merge closer and closer together until their inside faces come substantially or approximately into engagement with one another, for example, as along the lines indicated at 36 and 38 in Figs. 1 and 3. The contacting edges of the outboard and inboard walls 18 and 22 are bevelled off, as indicated at 40, on an angle which is acute to the substantially horizontal surface of the rail seat portion of the guard rail. In the embodiment of the invention illustrated, the angle of the bevel is approximately forty-five de-

grees, although any other suitable angle may be used. To avoid a sharp corner on the side adjacent the traffic rail, the extremity of the wall 18 is faced off or chamfered as indicated at 42.

In order to prevent track workmen or other pedestrians from inadvertently wedging their feet between the guard rail and traffic rail, laterally extending foot guards 10 44 are provided near each end of the guard rail.

These foot guards at the extremities are formed with inclined portions 46, which are substantially flush with the beveled ends 40 of the guard rail. These foot guards are 15 preferably formed of separate pieces of plate stock which are welded or otherwise secured to the outboard wall 18. Instead of welding the foot guards, as indicated for example at the left end of Fig. 2, they may be secured 20 by rivets 48, as indicated at the right end of Fig. 2. When the foot guards are riveted, they will be provided with lugs 50 and 52 extending inwardly, respectively, from the 25 downwardly extending flange 54 and the end portion 46 of said foot guard.

The guard rail, except for the separately formed foot guard portions, is formed up from one single piece of plate stock of suitable thickness by simple forging or bending operations. This provides a structure in which the several component parts such as the rail seat portion, outboard and inboard walls and bearing flange are all of substantially or approximately the same thickness 30 in cross section. The merging or bringing together of the walls 18 and 22 at each extremity of the guard rail provides a simple yet effective manner of producing the required flare and at the same time strengthens 35 and rigidifies the extremity of the rail and also closes the channel-shaped chamber between the inboard and outboard walls and presents a neat finish for the bevelled end 40 of the guard rail.

45 While I have described quite specifically the details of the embodiment of the invention herein illustrated, it is to be understood that I am not limited thereto except as expressly defined in the appended claims and such claims are to be interpreted as broadly 50 as is consistent with the teachings of the prior art.

What I claim is:—

55 1. A one-piece guard rail comprising longitudinal upright outboard and inboard walls joined at the top, a rail seat portion extended laterally from said outboard wall and a bearing flange extended laterally from the bottom of said inboard wall, all of said parts being of substantially uniform thickness in cross section, so that the rail is producible from flat stock of substantially uniform thickness.

forging producible from a flat plate of uniform thickness and having a substantially vertical outboard wall, an inboard wall inclined at an angle thereto, said inboard wall being spaced from the outboard wall for the major part of its length but pressed into engagement therewith at its extremities, substantially horizontal rail seats and bearing flanges bent laterally from said outboard and inboard walls and the exposed edges at the extremities of said walls being bevelled off at an angle substantially as shown and described.

8. A guard rail comprising an elongated main body portion formed of a single piece of metal of uniform thickness throughout and pressed from flat stock to the desired shape and having separately formed foot guards secured at the extremities thereof, the extremities of said body portion being bevelled at an acute angle to the horizontal and said foot guards having bevelled portions substantially flush with said bevelled extremities.

25 In witness whereof, I have hereunto signed my name.

CARROLL BURTON.
